UNITED STATES PATENT OFFICE.

MAURICE JOSEPH STACK, OF COHOES, NEW YORK.

INSTRUMENT FOR INSERTING CONTINUOUS BATS INTO UPHOLSTERY PLAITS.

Application filed February 16, 1926. Serial No. 88,626.

My invention relates to the art of upholstery plait stuffing or piping, for automobile cushions, seats and backs and other similar purposes; it primarily has for its object to provide a simple and effective instrument for the purpose which will be free from the objectionable features found in those instruments now in use. Heretofore tools have been provided known as piping tools. These are usually made in two or more sections or longitudinally split parts, between which the batting is threaded or drawn; when the operator uses such tools he is obliged to press the sections together, otherwise the continuous batting which is threaded through the instrument will pull out of the instrument when piping the plait of the cushion which causes the batting on the inside of the instrument to wrinkle the full length thereof and when the instrument is withdrawn the inserted batting does not fill the plait on account of the wrinkled condition. If the operator can not pound or pull the wrinkle out of the cotton batting in the plait, the cotton will have to be taken out of the plait which means extra cost and loss of production. My invention, therefore, seeks to avoid these objectional features and to that end I have produced the instrument comprising the subject matter of this invention.

Generically the invention comprises a long tubular body of proper cross sectional shape and of uniform cross section throughout that portion of its length which is insertable in the plait, the entrant end being provided with a flare or funnel-like portion, while the exit end has provision for an operator to press his fingers or thumb on the bat to hold it while withdrawing the instrument; the instrument is also provided with bat grippers adjacent each end for the purpose of drawing the bat from the roll in which it is wound (or from any other source) and for the purpose of holding the bat while being severed, respectively.

More specifically the invention also lies in those novel combinations and arrangements of parts which will be hereinafter described and pointed out in the appended claims, reference being had to the accompanying drawings, in which:

Figure 1 is a side elevation showing the invention in use.

Figure 2 is a plan view of the same.

Figure 3 is an enlarged vertical longitudinal section of the instrument, parts being broken away showing in full lines the bat gripper at the entrant end in operation.

Figure 4 is a view similar to Figure 3, showing the bat gripper at the exit end in operation.

Figure 5 is an end elevation looking at the entrant end.

Figure 6 is an end elevation looking at the exit end.

In the drawings, in which like numerals of reference indicate like parts in all the figures, 1 is the table on which the upholstery to be stuffed is laid and on which the exit end of the instrument that constitutes my invention may rest. 2 is the stand on which the roll 3 of continuous bat is located for purposes of unwinding.

4 is the instrument which constitutes the subject matter of my present invention. The instrument 4 consists of a section of tube or pipe of uniform cross section throughout that portion of its length which is adapted to be inserted into the plaits of the upholstery. At the entrant end the tube 4 has a flared or funnel-like portion 5 to facilitate the introduction of the bat and it is also slotted on the top as at 6 to cooperate with the bat gripper that serves to aid in unwinding the bat from the roll 3. The gripper consists of a leaf spring 7 of a width to pass through the slots 6, one end 8 of the spring 7 being secured to the tube 4 by spot welding, brazing or in any other suitable way. The front end of the spring 7 is bent at right angles upwardly as at 9 and then back upon itself as at 10 to constitute a convenient means by which the gripper 7 may be depressed into the slot 6 to grip the bat as shown in Figure 1.

The front end 11 of the tube 4 is recessed top and bottom as at 15 and 16 respectively and the top is slotted as at 12 from the recess inwardly a suitable distance. Lying over the slot 12 is a leaf spring 13, one end 14 of which is spot welded, brazed or otherwise permanently secured to the table 1. Normally the springs 7 and 13 lie parallel with their respective slots but do not project into the inner diameter of the tube.

17 is an eye secured to the entrant end of the tube by which it may be suspended with

2
a cable 18 from a suitable support 19 whereby the weight of the instrument is taken off of the operator.

20 is the plaited upholstery to be stuffed.

5 In using my invention the roll of continuous bat 3 is placed on the unwinding stand 2 and has its end threaded through the instrument so that the end of the bat will project beyond the end of the spring 13 in order 10 that when the instrument is inserted its full limit into the bat the operator can press his thumb on the plaiting adjacent the recessed or incut parts 16 and 15 and hold the end of the bat while the tool is being withdrawn. 15 Before inserting the instrument into the plait pocket the operator grasps the instrument adjacent the entrant end with his hand over the projection 10 of the gripper 7 and closes down on the gripper which forces it to 20 the position shown in Figure 1 and causes the bat to be firmly held there. Then as the instrument is advanced into the pocket the bat is unrolled correspondingly. In withdrawing the instrument from the pocket the operator, of course, releases pressure on the 25 projection 10 which permits the gripper 7 to restore itself to the inoperative position, see Figure 4. As soon as the instrument has been withdrawn from the plait pocket the 30 operator presses his thumb on the end of the spring gripper 13, thereby gripping the bat adjacent the exit end 11 of the instrument and by raising up on the instrument and holding down on the plait the section of the 35 bat within the plait is severed from the remainder and the instrument will then be ready for insertion into the next plait pocket and the operation repeated.

40 From the foregoing it will be seen that by the use of my instrument in connection with the roll unwinding stand (which constitutes the subject matter of my Patent #1,582,939 issued May 4, 1926), the operator is enabled rapidly to stuff the plaits with the batting 45 without wrinkling or twisting the batting from its normal state. The cross sectional shape of the instrument and its width and depth within corresponds to the external shape and dimension of the bat and therefore the bat is not pressed or wrinkled as with instruments of the longitudinal split 50 sectional type hereinbefore referred to.

55 From the foregoing description, taken in connection with the accompanying drawings, it is thought the construction, operation and advantages of the invention will be clear to those skilled in the art to which it relates.

What I claim is:

60 1. An instrument of the class described comprising a tube having an entrant end and an exit end, and a bat gripper cooperating with the tube and mounted on said tube and located at the exit end for the purposes specified.

65 2. An instrument of the class described

comprising a tube having an entrant end and an exit end, a bat gripper located at the entrant end, and a second bat gripper located at the exit end.

3. A tube of substantially uniform cross section throughout that portion of its length which is insertable in a plait and having a flared entrant end, said tube having a slot adjacent one end, and a bat gripping element mounted on the tube and operating 70 through the slot thereof.

4. A tube of substantially uniform cross section throughout that portion of its length which is insertable in a plait and having a flared entrant end, said tube having a slot 80 adjacent one end, and a bat gripping element mounted on the tube and operating through the slot thereof, said gripping element comprising a resilient body normally lying outside of the bore of said tube. 85

5. A tube of substantially uniform cross section throughout that portion of its length which is insertable in a plait and having a flared entrant end, said tube having a slot 90 adjacent one end, and a bat gripping element mounted on the tube and operating through the slot thereof, said gripping element comprising a resilient body normally lying outside of the bore of said tube, and having a hand engaging portion projecting 95 from the same whereby it may be pressed into the slot to grip the bat.

6. A bat unwinding and plait stuffing instrument, comprising a tube through which the bat from a roll is threaded and by which it is placed in upholstery plaits, a bat holding means adjacent each end of the tube, said bat holding means being alternately operable to grip the bat in unwinding it from the roll and separating the stuffed length 105 from the remainder of the bat.

7. A bat unwinding and plait stuffing instrument, comprising a tube through which the bat from a roll is threaded and by which it is placed in upholstery plaits, a bat holding means adjacent each end of the tube, said bat holding means being alternately operable to grip the bat in unwinding it from the roll and separating the stuffed length 110 from the remainder of the bat, said means comprising two bat gripper elements, arranged one adjacent one end and the other adjacent the other end of the tube, said tube having slots to permit said elements to function. 115

8. A bat unwinding and plait stuffing instrument, comprising a tube through which the bat from a roll is threaded and by which it is placed in upholstery plaits, a bat holding means adjacent each end of the tube, said bat holding means being alternately operable to grip the bat in unwinding it from the roll and separating the stuffed length 125 from the remainder of the bat, said means comprising two bat gripping elements, ar- 130

- ranged one adjacent one end and the other adjacent the other end of the tube, said tube having slots to permit said elements to function, each of said gripping elements comprising a leaf spring secured to the tube and adapted to align with its respective slot.
9. A bat unwinding and piping instrument, comprising a tube through which the bat is threaded and having its exit end recessed and slotted, and a leaf spring secured at one end to the tube adjacent the inner end of the slot and adapted to lie in alignment with said slot, the free end of said spring terminating at the recessed end of the tube for the purposes described.
10. An instrument of the class described, comprising a tube composed of a continuous body to maintain its cross sectional form constant, said tube having an entrant end
- and an exit end, and a bat gripper associated 20 with the tube in the entrant end for the purposes specified.
11. An instrument of the class described, comprising a tube composed of a continuous body to maintain its cross sectional form 25 constant, said tube having an entrant end and an exit end, and a bat gripper associated with the tube in the exit end for the purposes specified.
12. An instrument of the class described, comprising a tube composed of a continuous body to maintain its cross sectional form constant, said tube having an entrant end and an exit end, a bat gripper located in the entrant end of said tube and a second bat 35 gripper located in the exit end of the tube for the purposes specified.

MAURICE JOSEPH STACK.
